UNITED STATES PATENT OFFICE.

RICHARD KÜCH, OF HANAU, GERMANY, ASSIGNOR, BY MESNE ASSIGNMENTS, TO
GENERAL ELECTRIC COMPANY, A CORPORATION OF NEW YORK.

GAS OR VAPOR ELECTRIC LAMP.

1,090,992.

Specification of Letters Patent. Patented Mar. 24, 1914.

Application filed March 20, 1906. Serial No. 307,107.

To all whom it may concern:

Be it known that I, RICHARD KÜCH, a subject of the German Emperor, and residing at Hanau, Germany, have invented certain 5 new and useful Improvements in Gas or Vapor Electric Lamps, of which the following is a specification.

In the first gas or vapor electric lamps (by Arons and others) both electrodes were of 10 mercury. During the operation of such lamps the evolution of heat at the positive mercury electrode is greater than that at the negative mercury electrode (see "*Annalen der Physik*" fourth continuation, 15 Volume XII, 1903, page 678). If therefore there is an anode and a cathode of mercury which have the same shape and the same quantity of mercury, a smaller quantity of 20 mercury will evaporate during the same time at the latter electrode than at the former electrode. The consequence of this is, that the mercury is gradually drawn over from the anode to the cathode and collects at the latter. For maintaining the continuous 25 working of the lamp, it was therefore necessary to so arrange the lamp with the two mercury electrodes, that the cathode was enabled to overflow from time to time and to return the excess as liquefied mercury 30 to the anode. This produced, however, a periodical disagreeable flashing of the light. In small lamps the overflow of the cathode even frequently caused the extinction of the 35 light. For this reason in all gas or vapor electric lamps for illuminating purposes a solid anode (of iron, carbon and the like) was preferably employed and mercury was used only as a cathode. The gases developed in the course of time from the solid 40 electrodes however created difficulties. In highly loaded gas or vapor electric lamps with mercury electrodes the solid anodes are in general not permissible on account of the high temperatures produced. If, however, 45 the anode is externally cooled or if it is made sufficiently larger than the cathode so that more heat is dissipated from the anode than from the cathode, the result may be obtained that almost no mercury is transferred from 50 one electrode to the other. The phenomenon referred to has reference to the non-luminous vapor and does not refer to the transportation of luminous particles from the cathode to the anode.

The present invention relates to improvements in gas or vapor electric lamps. 55

The object of the invention is to provide a lamp of the character described, having one or both electrodes of mercury or other liquid metal, which will operate continuously 60 without disturbance of the operation.

The above object is accomplished first, — by so proportioning the sizes or shapes of the electrodes that each will dissipate heat in proportion to the heat generated within it, 65 and, second,—to automatically control the dissipation of heat from the negative electrode. With a proportioning of the electrodes, as above described, an almost exact regulation of the mercury levels at the two 70 electrodes is attained. Were this regulation exact under all circumstances, no further regulating means would be required. It has been found, however, that a given proportioning of the electrode chambers will not 75 produce exact regulation under different conditions such as different temperatures of the surrounding atmosphere. To produce exact regulation under all circumstances I have, as above set forth, conceived the plan of 80 automatically regulating the dissipation of heat from the cathode and, as also herein set forth, the specific means which I have shown for accomplishing this last regulation consists of a narrow intermediate tube 85 which connects the negative electrode chamber with the illuminating tube.

The proportion of the heats developed and given off at both mercury electrodes in a gas or vapor electric lamp can be influenced by 90 the shapes and sizes of the two electrode chambers. I have found, that the degree of cooling of the anode differs in one respect from that of the cathode. As is well known, a so-called cathodic luminous aigret is 95 formed on the negative electrode (*vide* for instance the article by J. Stark in the "*Annalen der Physik*," Volume IV, 12, page 673) and this aigret agitates the surface of the cathode and puts it in a permanent boiling motion. At the anode, however, no such mechanical agitation takes place. From this fact it follows, that the heating of the mercury in the anode is simply effected by transmission of heat from the surface, but 100 in the cathode the heating of the mercury is also effected by mixing the hot layer at the surface with the lower cooler layers. 105

It is this difference, which enables me to automatically regulate the quantity of mercury evaporated at the cathode and thereby to make constant the levels of the mercury at both electrodes.

- 5 It is easy to so proportion the positive and the negative electrode chambers, that the proportion of the heats given off at both electrodes is approximately the same as the 10 proportion of heats developed at both electrodes. Of course, it is not possible to render this proportion exact for the reason, that the quantity of heat given off depends upon the temperature of the ambient air. 15 The exact automatic regulation according to my invention is obtained in the manner now to be described.

Referring to the drawing, the figure shows a cross section of the lamp.

- 20 The electrode on the right and the electrode 1 which consist of chambers for receiving mercury are connected by the illuminating tube as shown. The shapes or sizes of the electrode chambers are so proportioned relatively that they will dissipate the 25 heat generated within them at such rates that both chambers will remain at the same temperature when other conditions are normal, for instance, when the outside 30 temperature of the air is normal.

- The negative electrode bulb is given such a shape, that the internal diameter of that 35 part of the chamber, which is subjected to the action of the arc-light, is so much reduced, that the above mentioned agitation of the mercury by the cathodic luminous aigret is restricted in depth. It is obvious 40 that the depth of the agitation like all agitations in liquids goes only to a certain depth 45 dependent somewhat upon the cross section of the containing vessel; that is, the narrower the vessel is within which the liquid is inclosed the less the depth of the agitation.

- 45 In the drawing, 1 denotes a cathode chamber connected to the illuminating tube by a narrow constricted tube 2.

- The dissipation of heat at the cathode is accomplished in two ways, first, by pure conduction to the entire bulk of the mercury, 50 and hence by radiation; and second, by the boiling action of the cathodic aigret which stirs up the mercury at the cathode and effects an even distribution of the heat in a mercury mass, and hence by radiation to 55 the outside air. It is assumed, that at the start of the lamp the chambers 1, 2 be filled with mercury up to the point 3. The cathodic luminous aigret formed at the point 3 60 will agitate the mercury down to a certain depth, say as far as the vertical line 5, while the part of the mercury on the left of this line 5 will receive heat only through transmission. The size of the cathode bulb in 65 proportion to that of the anode bulb is from

the beginning so determined, that this transmission of heat is too small. Then mercury will evaporate on the surface of the cathode at 3 and the level will sink say for example to the point 4. The agitation being always 70 of the same depth will go deeper in the cathode chamber. More bulk of mercury will now be stirred up than before, the heat will be more evenly distributed through the whole mass, and therefore the total dissipation 75 increased. The temperature of the cathode chamber as a whole will drop, and therefore the temperature of the mercury in the restricted portion 2. If this drop is below the temperature of the anode, mercury 80 will condense and fill the part 2, until a balance has been re-established. Let us assume, that at this moment the proper proportion be attained. Should from any external reason 85 the transmission of heat vary, this variation will produce certain effects. For example, when the temperature of the ambient air sinks on that place, the transmission of heat to the outside air will increase, so that also a greater radiation of heat will take 90 place at the point 4, when mercury will again condense at 4 and the level of the mercury will rise up to a point, say between the two points 3 and 4. In other words, this arrangement of the two electrode chambers 95 will result in a perfectly automatic regulation of the levels of mercury in both the cathode and the anode. Trials have proved, that in this manner actually constant levels of mercury are obtained, and that lamps so 100 arranged will burn for hundreds of hours and permanently with constant levels of mercury.

Hitherto gas or vapor electric lamps with mercury electrodes have been considered, 105 but it is obvious, that also electrodes of metals, which are liquid during the work, will equally work in exactly the same manner as the mercury electrodes.

What I claim as my invention, and desire 110 to secure by Letters Patent, is—

1. The herein-described gas or vapor electric lamp comprising a tube having electrode chambers at its ends, the passage connecting one of said chambers with the tube having 115 a relatively smaller area exposed to the action of the electric arc produced in the tube when the lamp is in operation than the passage connecting the other chamber and tube, a liquid cathode in said contracted 120 passage and adjacent chamber, and a liquid anode in the other chamber.

2. The herein-described gas or vapor electric lamp comprising a tube having electrode chambers at its ends, the cathode chamber 125 being connected with the tube by a passage that is smaller than that connecting the tube and anode chamber, a body of mercury in the cathode chamber and partly filling the passage connecting said chamber with the 130

body of the tube, and a body of mercury in the anode compartment.

3. A vapor electric device comprising an anode bulb partly filled with mercury, a cathode bulb entirely filled with mercury, a main illuminating tube communicating with said anode chamber and a tube of lesser diameter than said illuminating tube connecting the latter with the cathode chamber.
- 10 4. A mercury vapor lamp comprising the combination of an anode bulb partly filled with mercury, a cathode bulb entirely filled with mercury, connecting illuminating tube and a tube partly filled with mercury connecting the cathode bulb with the illuminating tube and of lesser diameter than said
- 15

illuminating tube, the heat dissipating surfaces of said anode bulb and said cathode bulb being in proportion to the amount of heat developed therein respectively, said 20 narrow connecting tube being adapted to regulate the agitation of the mercury in the cathode bulb, thereby to regulate the heat dissipating capacity thereof.

In testimony whereof I have signed my 25 name to this specification in the presence of two subscribing witnesses.

RICHARD KÜCH.
